(57) **CLAIM**

The ornamental design for a finger ring, as shown and described.

DESCRIPTION

1. Finger ring
- 1.1 : Perspective
- 1.2 : Front
- 1.3 : Back
- 1.4 : Right
- 1.5 : Left
- 1.6 : Top
- 1.7 : Bottom

The finger ring comprises two parallel circular rings arranged coaxially, between which several anchor chain link shaped elements are fixed.
